UNITED STATES PATENT OFFICE.

LOUIS J. CHURCH, OF WASHINGTON, DISTRICT OF COLUMBIA.

NUTMEG-GRATER.

SPECIFICATION forming part of Letters Patent No. 337,378, dated March 9, 1886.

Application filed May 20, 1885. Serial No. 166,142. (No model.)

To all whom it may concern:

Be it known that I, LOUIS J. CHURCH, of Washington, in the District of Columbia, have invented a new and useful Improvement in 5 Nutmeg-Graters; and I do hereby declare that the following is a full, clear, and exact description of the same.

My invention relates to nutmeg-graters, but is applicable for other articles. It is an improvement on the grater shown in Letters Patent of the United States granted on the 25th day of March, 1884, and numbered 295,736.

My object is mainly to simplify the construction; but I have also improved the operation 15 of the apparatus.

In the accompanying drawings, Figure 1 is a top view with the arms of the handle in their normal position. Fig. 2 represents a perspective view, the disk and handle being removed. 20 Fig. 3 is a plan view showing some of the parts in section and the spring-arm in the position it assumes when the article to be grated is in place within the cup. Figs. 4 and 5 show, respectively, a vertical and a horizontal section 25 through a modified form of cup.

I use a body forming the cup A and bearing a for the grater-disk, cast in one piece, substantially as shown in my said patent. It is, however, improved in form by providing it 30 with a wall opposite the grater-disk and slotted to admit the arm b, carrying the pressure-plate c, that bears against the article to be reduced.

The first part of the invention relates to the 35 construction of the handle and this arm b. The handle and arm carrying the pressure-plate are composed of a single piece of elastic wire, which by its elasticity renders the spring unnecessary, which was required in connection with 40 the lever shown in my said patent. This wire consists of a loop, B, which forms the handle. One end of the wire is fixed to the body A. The other end is bent laterally at right angles 45 near the body A, and extends past the cup, where it is bent again at right angles, and extends forward to the slot d in the wall of the cup. It is again bent to enter this cup, and extends toward the surface of the grater-disk and at right angles thereto. To this end is 50 fixed the pressure-plate c. Manifestly the wire could be carried around instead of bent at right angles. The upper branch, e, of the loop,

which carries the pressure-plate, is made to normally extend to the right of the lower branch, f, at the forward end, as shown in Fig. 55 1. This construction affords a better and more perfect handle for the operator, for the reason that when the pressure-plate is retracted for the reception of the article to be pulverized the upper arm, e, will then be nearly or quite 60 in the same vertical plane with the lower arm, f.

The preferred shape of the handle is shown in Figs. 2 and 4, in which the upper branch has a longer curve, and the rear of the loop is consequently bent downward. 65

A button, g, may be placed on the upper branch for the first finger when it is desirable to add to the pressure of the spring. By this construction of the handle I provide a cheaper and better article, perfect in operation, and 70 not liable to get out of repair.

I do not limit myself to the precise form of the handle nor shape of the wire.

The grater-disk is made as explained in my former patent referred to, or any equivalent 75 disk known or devised for the purpose may be used. This grater-disk (marked 1) is provided, also, with supporting-arms m, one of which, extending, forms the handle n, as in my said patent. Instead of these arms, I may use another 80 disk for supporting the grater-disk, covering the entire grater-disk, or a large part of it, as shown in Fig. 3, the disk in this case being raised a little above the grater-disk, in order to allow grated material to escape between 85 the two disks when any passes through the holes in the grater-disk.

The bottom of the slot d forms a bearing for the upper branch, e, of the handle, and serves to keep the said branch in its proper position 90 in relation to the branch f, and thus avoid the liability of the two branches coming in contact with each other after long use. This construction also keeps the pressure-plate in a central position. 95

In Figs. 4 and 5 is shown a modified form of cup, in which the rear slotted wall is omitted and the side walls are carried over, forming a cylindrical-shaped cup. In this case the article to be grated is inserted through the opening at 2, the pressure-plate being retracted for this purpose. A ledge or plate, 3, is formed to the cup, and affords a bearing for the upper branch, e, of the spring-handle, taking the 100

place of the slot *d* in the construction shown in Figs. 1, 2, and 3.

I claim as my invention—

1. A grater having a cup and grating-surface, 5 in combination with a handle, *B*, formed of two branches, *e f*, in one piece, the branch *f* being secured to the body of the grater, and the branch *e* being free at its end and terminating in a pressure-plate, the parts being arranged 10 and operating substantially as described.

2. A grater having a cup and grating-surface and a pressure-plate for pressing the article to be grated upon said surface, combined with a handle formed of a single wire, one branch 15 of which is secured to the body of the grater, and the other of which is bent to enter the cup at right angles to the grating-surface, substantially as described.

3. In a grater, and in combination, a grating-surface, a cup, a handle having branches *e f*, 20 a pressure-plate carried on the branch *e*, and a bearing for said branch *e*, substantially as described, whereby the pressure-plate is kept in proper position within the cup, and the branches are kept in proper position with relation to each other, substantially as described. 25

In testimony whereof I have signed my name to this specification in the presence of two subscribing witnesses.

LOUIS J. CHURCH.

Witnesses:

WALTER DONALDSON,
F. L. MIDDLETON.
